(57) **CLAIM**

The ornamental design for a hat storage and display device, as shown.

DESCRIPTION

FIG. 1 is a bottom, front and right side perspective view of a hat storage and display device, showing our new design;

FIG. 2 is a top, back and left side perspective view thereof;

FIG. 3 is a top plan view thereof;

FIG. 4 is back elevation view thereof; and,

FIG. 5 is a left side elevation view thereof.

The broken line showing of the environment is for illustrative purposes only and forms no part of the claimed design.
